UNITED STATES PATENT OFFICE

FRANK FENTON, OF AKRON, OHIO, ASSIGNOR, BY MESNE ASSIGNMENTS, TO THE MILLER RUBBER COMPANY INC., OF WILMINGTON, DELAWARE, A CORPORATION OF DELAWARE

WATER WINGS

Application filed September 5, 1929. Serial No. 390,546.

My said invention relates to improvements in Aviad or water wings.

Heretofore, so far as I am aware, such articles have usually been made of cloth which requires wetting prior to inflation to make them retain air, and have customarily sold for fifty cents or more.

The present invention aims to provide water wings made wholly of rubber which will be perfectly sanitary and which, by reason of the construction of the article and method of making it, may be so economically produced as to be capable of being sold in the ten cent stores at a profit, or for a similar price at beaches, thus making it available for everyone.

The invention also aims to provide an article which will be strong and durable and adapted, as a swimming appliance or aid, for adults as well as children.

With these and other objects in view, the invention comprises the novel article hereinafter described and defined by the appended claim.

In order that the invention may be more readily understood, reference is made to the accompanying drawings in which:

Figure 1 is a plan view of two halves or sections of a set of water wings before being united.

Fig. 2 is a diagrammatic view of a die used for forming the sections.

Fig. 3 is an enlarged section on line 3—3 of Fig. 1.

Fig. 4 is an enlarged sectional view showing the two sections superposed and ready for die cutting or seaming together.

Fig. 5 is a plan view of the completed article prior to inflation.

Fig. 6 is an enlarged longitudinal sectional detail through one of the inflating tubes, and

Fig. 7 is a perspective view of the article inflated and ready for use.

In the production of this article, two sheets of thin uncured rubber stock are properly aligned to pass under or be subjected to the action of a suitably shaped die member 1, the shape of which is shown diagrammatically in Fig. 2 by the action of

which they are cut together on a line to give the proper contour to form one half of a set of water wings, but leaving open the neck portion 2, and the air filling tube 3 thereof, for purposes hereinafter referred to.

55

It will be understood that the two wings or sections are identical, and therefore cut by the same die member, and that a description of one is also a description of the other. Each half member or section has the neck 60 portion 2 and the wing or enlargement 4, which will fit snugly under the user's arm in support of the body when used in the water.

After the halves or sections have been 65 died out and inspected, two of them are placed one upon the other in proper alignment so that their neck portions 2 are brought together and are then subjected to a pinch blunt die cut across the neck near the open end thereof whereby the halves are 70 united on the line a—b.

This, when the two sections are opened out flat; i. e., one removed or unfolded from the other, produces the complete wings as 75 shown in Fig. 5, except for the closure members for the valves, which are later inserted, after the article has been vulcanized.

In Fig. 3, the neck portion 2 is shown enlarged and exaggerated to indicate the two 80 sheets A and B forming the article, and clearly illustrates the open end neck 2 and the filling tube opening 3.

In Fig. 4, the halves are shown as aligned under the blunt die member 5, of straight- 85 edge form, ready to be cut together to complete the article, as illustrated in Fig. 5.

In Fig. 6 is shown a cross section of the air filling tube 3, which is provided with the ordinary closure means, used in various inflatable rubber articles and toys, consisting of a short length of semi-hard rubber tubing 6 of small diameter, which may be readily forced into the thin rubber tube 3 and securely held thereon by friction.

95

Into this tube 6 a short length filler pin or plug 7 of similar material to the tubing 6 is pushed to make an effective closure in retaining the air pressure blown into the wings, when used.

100

Fig. 7 illustrates approximately the shape the inflated article assumes when ready for use, the user placing the neck portions 2 across the chest and the arms thereover to permit the enlarged portions or wings 4 to float upon the water to assist and support the person's body in the act of swimming, or floating.

By forming the tube portions 3 simultaneously with the sections, I greatly simplify the process of forming and applying the inflating means, and by the method of dieing or pinch cutting the sheets together, and making them wholly of rubber, I produce a sanitary article, one that is air tight at the start, and is strong and durable, and is extremely economical of manufacture.

Having thus described my invention, what I claim is:

20 A device for assisting swimmers, said device comprising a pair of impervious inflatable rubber air chambers, and an inflatable pectoral yoke member integral therewith, said yoke member comprising non-communicating extensions of said air chambers joined by a die-cut seam.

In testimony whereof, I affix my signature.

FRANK FENTON.
